(57) **CLAIM**

The ornamental design for an audio device wall mount, as shown and described.

DESCRIPTION

FIG. 1 is a front elevation view of an audio device wall mount, according to our new design;

FIG. 2 is a rear elevation view thereof;

FIG. 3 is top plan view thereof;

FIG. 4 is a bottom plan view thereof;

FIG. 5 is a first side view thereof;

FIG. 6 is a second side view thereof; and,

FIG. 7 is a perspective view thereof.

The dashed broken lines in the figures show features of the audio device wall mount that form no part of the claimed design.

The dot-dash broken lines illustrate boundary lines and form no part of the claimed design.

1 Claim, 3 Drawing Sheets
